UNITED STATES PATENT OFFICE.

ERNST A. LARSSON, OF MANSFIELD, OHIO, ASSIGNEE TO THE OHIO BRASS COMPANY,
OF MANSFIELD, OHIO, A CORPORATION OF NEW JERSEY.

CURRENT COLLECTOR.

Application filed June 4, 1927. Serial No. 186,562.

My invention relates to current collectors and to that type of collector in which the contacting element with the overhead conductor or trolley wire moves in slidable relation 5 thereto in place of rotatable relation.

The object of my invention is to provide a device of the character described, which will have an extended contact with the trolley wire and a large carrying capacity for current 10 between the contacting element and the support or harp therefor, and one in which the tendency for the contacting element or shoe to rotate, when the shoe strikes an obstruction, is resisted.

Another object of my invention is to so 15 arrange the shoe with respect to its support that the tendency to rotate from friction of the shoe with the trolley wire is as small as possible.

Other objects will appear as the invention 20 is further described hereinafter.

My invention resides in the new and novel construction, combination and relation of the various parts hereinafter described and 25 shown in the accompanying drawing.

In the drawing:

Fig. 1 is a top view of my invention.

Fig. 2 is a side view of my invention.

Fig. 3 is an end view.

Fig. 4 is a longitudinal section taken on the line 4—4 of Fig. 1.

Fig. 5 is a transverse section taken on the line 5—5 of Fig. 2.

It is well known to those skilled in the art 35 that prior devices of this character, in which a sliding contact or shoe is employed, are usually mounted upon a small axle, the center of which is removed quite a distance from the contact surface of the shoe with the trolley 40 wire. As later explained, this produces a strong tendency for the shoe to rotate if the coefficient of friction of the shoe with respect to the trolley wire is equal or greater than the coefficient of friction between the shoe and the 45 axle or support.

Some devices of this character employ a flexible connection or cable between the shoe and the supporting harp in order to conduct the current from the shoe to the harp, as the 50 axle, as a rule, gives very small carrying capacity and the contact is very poor. In order to avoid the use of a flexible cable or side springs, I employ a relatively large axle, which gives a large area of contact with the 55 shoe, and also the ends of the axle are quite

extensive in area and are secured in close and intimate contact with the supporting harp, therefore, I am able with my device to safely and efficiently carry large currents from the trolley wire to the harp without the use of a 60 flexible cable or shunt around the axle. At the same time, by properly placing the axis of the axle so that the upper point of contact of the axle with the shoe is as close to the contact surface of the shoe with 65 the trolley wire as possible, taking into account probable wear in the surface of the shoe, I am able to reduce very materially the tendency for the shoe to rotate when moving along a conductor. 70

In the preferred embodiment of my invention I employ a supporting harp 1, similar to those in use in prior art, and mounted between the inner faces of the arms 2 of the harp I position an axle 3. In order to hold the 75 axle in position, I employ two transversely disposed bolts 4. The end faces of the axle 3 and the inner faces of the arms 2, coacting therewith, I prefer to machine so that I will get the benefit of the full contact area of the 80 ends of the axle and by means of the bolts 4 I am able to draw the contacting surfaces into close and intimate relation with each other. Transversely disposed in the axle is a passage 5 which has communicating therewith 85 the smaller passages 6 which open upon the surface of the axle, and before mounting the axle in the harp I fill the passage 5 with a lubricating grease which has a tendency to work its way through the smaller passages 90 6 to the surface of the axle.

Mounted upon the axle 3 is a shoe 7 provided with an extended groove 8 formed between the flanges 9 and having the elongated surface 10 which contacts with the trolley 95 wire. The shoe is provided with a transverse opening of sufficient size to snugly fit the axle 3, but permitting relative rotation of the shoe with respect to the axle when the shoe is in operation and any difficulties in the wire or 100 varying height of the trolley wire require a rotation of the shoe relative to the axle.

I construct my shoe with a certain amount of metal below the groove 8 to allow for wear, and this metal may amount to possibly $\frac{1}{4}$ ". 105 With this in mind, if the line 11 represents the maximum limit of wear of the shoe, I drill the transverse hole through the shoe with its upper surface very close to the line 11, which I find should not exceed $\frac{3}{8}$ " below the con- 110

tact surface 10 when the shoe is new, thereby bringing the upper surface of the axle as close to the line of contact with the wire as practicable, and where the shoe is made of hardened steel, it is practicable to bring the axle surface much closer to the surface 10 than where the shoe is made of copper or bronze.

The object of bringing the surface of the axle as close to the wearing surface of the shoe as possible is to reduce the moment tending to rotate the shoe when the shoe is in motion sliding along the trolley wire, and the results of so positioning the axle with respect to the contact surface of the shoe can be shown by the following simple mathematics.

D = distance from center of axle to contact surface.

R = radius of axle.

a = coefficient of friction between wire and shoe.

b = coefficient of friction between axle and shoe.

P = pressure of shoe against wire.

$P \times a \times D$ = moment tending to rotate shoe.

$P \times b \times R$ = equal moment tending to resist rotation of shoe.

$P \times a \times D - P \times b \times R$ = actual moment tending to rotate shoe.

If $a = b$ then

$P a (D - R)$ = actual moment tending to rotate shoe.

If $D = 1$ and $R = \frac{3}{4}$ then

$P a (1 - \frac{3}{4}) = \frac{1}{4} P a$ = actual moment tending to rotate shoe when $a = b$.

If there is a difference in the coefficient of friction then

$P (a - \frac{3}{4} b)$ represents the moment tending to rotate the shoe.

If the axle were made of small diameter with its axis as shown in Fig. 4, then the tendency to rotate would be very much greater than shown above, as for instance,

If $D = 1$ and $R = \frac{1}{4}$ and $a = b$ then

$P a (1 - \frac{1}{4}) = \frac{3}{4} P a$, and it will be noted that this moment is three times that given above where the surface of the axle approaches closely to the contact surface of the shoe.

If, of course, there is a difference in the coefficient of friction, then the moment tending to rotate the shoe would be $P (a - \frac{1}{4} b)$.

If it were possible to have the surface of the axle and the contact surface coincide, in which case R and D would both = 1, then

$P a (1 - 1)$ would = zero, or in other words, there would be no moment tending to rotate the shoe unless there was a difference in the coefficient of friction.

It is believed from the above it will be seen that by properly locating the axis of the axle and the diameter of the axle with respect to the surface of the shoe, that the tendency to rotate the shoe can be brought down to a minimum and governed largely by the coefficient of friction in the moving parts and the

amount of wear necessary to allow for in the shoe.

In order to make the shoe operative in both directions, as when applied to a moving vehicle, I place the axis of the axle such that under normal operation it will rest in a transverse vertical plane coinciding with a vertical center line $c-c$ passing through the axis and will cut the contact surface midway of its length, as shown in Fig. 4. This makes the forward and backward operation of the shoe uniform, as the parts are then symmetrical with respect to the transverse vertical plane and vertical center line $c-c$, as will be noted in the drawing. In order to resist tendency for the shoe to rotate when it strikes obstructions, such as the end of a trolley ear and tend to eliminate such rotation, in the majority of cases I employ what I term a stabilizer 12, which is shown in Fig. 4 as a separate element secured to the shoe by means of bolts 13. This stabilizer also acts as a guard to prevent the shoe catching on the trolley wire should the shoe leave the trolley wire. The bolts 13, if desired, may have their heads counter-sunk below the surface of the stabilizer, which will then give a perfectly smooth surface, also, if desired, the stabilizer may be formed as an integral unit with the shoe.

When in normal operation, the contact between the shoe and the trolley wire will cause the stabilizer to assume its lowest position, and it will be noted that the mass of the stabilizer is greatest at its lowest point, therefore, should the forward end of the shoe suddenly strike an inequality in the trolley wire, then there would be a sudden tendency for the shoe to rotate, but simultaneously there would be a tendency for the stabilizer with its mass located at its lowest point to rotate, and it would require a force to start moving the mass of the stabilizer, which would tend to counteract the tendency for the shoe to rotate due to its having suddenly met with an inequality along the wire.

I have so formed the stabilizer that the upper portion or arms 14 form with the rim 15 of the shoe arcuate spaces 16, and passing through the arms of the harp and one of the arcuate spaces 16 is a pin 17 which engages the shoulders 18 and 19 on the shoe and stabilizer respectively to limit the amount of rotation of the shoe under abnormal conditions.

The mass in the stabilizer 12 can be made large or small, depending upon the effect required and no consideration is given to the amount of mass with respect to balancing the shoe.

If the mass is very great to overcome the friction between the shoe and the axle, then the stabilizer would maintain the contact surface of the shoe in a horizontal position when the shoe was not engaging the trolley wire, but I make no attempt to adjust the weight

of the shoe to bring about this condition, as it is not necessary in the successful operation of my device, but the mass of the shoe is adjusted so as to overcome the tendency of 5 the shoe to rotate when suddenly meeting with obstructions in its path of movement.

I find that the diameter of the axle should be not less than one-half the length of the 10 contact surface 10 on a new shoe and which is 15 in engagement with the trolley wire. This gives ample contact of the axle with the shoe and the harp.

Having described my invention, I claim:

1. A current collector of the sliding type 15 comprising a shoe having a groove with an elongated contact surface, a transverse opening to receive an axle therein, the horizontal axis of the axle being located in a vertical transverse plane at right angles to the contact 20 surface and midway of the length of the contact surface, shoe being symmetrical with respect to the transverse plane and the said axis being below the contact surface a distance not to exceed the radius of the axle 25 plus an amount equal to the predetermined allowable wear of the shoe, a support, an axle mounted in the transverse opening and secured to the support in fixed relation, a separably formed U-shaped stabilizer secured 30 to the shoe with its center of gravity positioned in said vertical plane but below the axis of the axle and its legs projecting upwardly and forming guards, a transversely disposed member secured to the support and 35 arranged to engage a shoulder on the shoe and a shoulder on the stabilizer to limit the amount of oscillation of the shoe on its axle, means in the axle to retain a lubricant and means communicating with the said means 40 and the bearing surface of the axle.

2. A current collector comprising a shoe having its mass substantially equally disposed on both sides of a vertical central axis, a groove having an elongated contact surface 45 extending equal distance to each side of the said vertical axis, a transversely disposed passage through the shoe, an axle mounted in the passage with its axis in the plane of said vertical axis and the upper line of contact 50 between the axle and the shoe being on the said vertical axis and adjacent the contact surface on the shoe, a support, means securing the axle to the support in pivotal relation to the shoe, means to limit the amount of 55 pivotal motion and an inverted U-shaped stabilizer secured to the shoe and having the bulk of its mass positioned below the lower line of contact between the axle and the shoe and on the vertical axis to resist a sudden 60 tendency of the shoe to rotate and the distribution of the weight of the said parts being substantially equal both forwardly and rearwardly of the vertical axis.

3. A current collector comprising a sliding 65 shoe having a flanged groove with an elongated

contact surface substantially equally spaced on each side of a vertical central axis, a transverse passage through the shoe, an axle mounted in the passage and secured to a support, the upper line of contact between the 70 axle and the shoe cut by the said vertical axis being positioned adjacent the surface of contact of the groove, the axis of the axle being cut by the said vertical axis and a U-shaped stabilizer with its mass suspended below the 75 axis of the axle and equally spaced with respect to the vertical axis and longitudinally of the shoe to resist sudden tendencies of the shoe to rotate.

4. A current collector comprising a harp 80 with means to secure it to a support and other spaced projecting arms having inner parallel faces, an axle mounted between said faces and secured to the arms with the end faces of the axle engaging the faces of the arms, a plurality of spaced and transversely disposed means to hold the axle in place between the arms and prevent its rotation and a sliding shoe with a contact face pivotally mounted upon the axle, the diameter of the axle being 85 more than twice the thickness of metal between the contact face and the nearest adjacent edge of the axle.

5. A current collector comprising a harp 90 with means to secure it to a support, spaced 95 arms projecting from the said means and having inner parallel faces, an axle mounted between the arms and having parallel faces engaging the faces of the arms, a pair of transversely disposed means to draw the arms 100 toward the axle to bring adjacent faces into firm and secure engagement and prevent rotation of the axle, a shoe pivotally mounted upon the axle and means to limit the pivotal action of the shoe.

6. A metallic current collecting shoe provided with a grooved portion having an elongated surface to engage a conductor in sliding relation thereto and subject to wear, a transverse passage therethrough to receive 110 an axle upon which the shoe is mounted and pivots, the diameter of the passage to be substantially not less than $\frac{1}{2}$ the length of the original contact surface engaging the conductor and a removable member secured to 115 the shoe tending to hold the contact surface parallel to the conductor when the conductor is parallel.

7. A metallic current collecting shoe provided with a grooved portion having an elongated contact surface to engage a conductor and extending an equal distance to both sides of a vertical center axis and subject to wear, a transverse passage therethrough to receive 120 an axle upon which the shoe pivots, the axis of the passage being located on the vertical center axis and the diameter of the passage to be substantially not less than $\frac{1}{2}$ the length of the original contact surface engaging the conductor and means to maintain the con- 125

tact surface in a horizontal position when off the conductor.

8. A metallic current collecting shoe provided with a grooved portion having an elongated contact surface to engage a conductor and subject to wear and extending an equal distance to both sides of a vertical center axis, a transverse passage to receive an axle upon which the shoe pivots and having its center upon said line, the amount of metal in the shoe between the contact surface when new and the adjacent edge of the passage cut by said vertical axis to be not more than $\frac{3}{8}$ inch and the diameter of the axle to be substantially not less than $\frac{1}{2}$ the length of the original contact surface engaging the conductor.

9. A metallic current collecting shoe provided with a grooved portion having an elongated contact surface to engage a conductor and subject to wear and extending an equal distance to both sides of a vertical center axis, a transverse passage to receive an axle upon which the shoe pivots and having its center upon said line, the amount of metal in the shoe between the contact surface when new and the adjacent edge of the passage cut by said vertical axis to be not more than $\frac{3}{8}$ inch

and the diameter of the axle to be substantially not less than $\frac{1}{2}$ the length of the original contact surface engaging the conductor and a stabilizer to resist sudden tendencies of the shoe to rotate.

10. A current collector comprising a shoe having a flanged groove with an elongated contact surface to engage a conductor in frictional sliding relation thereto and subject to wear, an axle upon which the shoe is pivotally mounted, the axis of the axle being midway the length of the contact surface, the distance of the axis from the contact surface and the radius of the axle being in the ratio of 1 to $\frac{3}{4}$.

11. A current collecting shoe provided with a groove having an elongated contact surface, an axle upon which the shoe pivots and a stabilizer, the effective mass of the stabilizer being positioned below the axis of the axle and the mass of each the shoe, the axle and the stabilizer being equally disposed on both sides of a vertical central axis which is central of the length of the contact surface.

In testimony whereof I affix my signature.

ERNST A. LARSSON.
